(57) **CLAIM**

The ornamental design for a contour brush, as shown.

DESCRIPTION

FIG. 1 is a top perspective view of a first embodiment of a contour brush showing my new design.

FIG. 2 is a bottom perspective view thereof.

FIG. 3 is a top plan view thereof.

FIG. 4 is a right side elevation view thereof. The left side elevation view is the mirror image of the right side elevation view.

FIG. 5 is a bottom plan view thereof.

FIG. 6 is a front elevation view thereof.

FIG. 7 is a rear elevation view thereof.

FIG. 8 is a top perspective view of a second embodiment of a contour brush showing my new design.

FIG. 9 is a bottom perspective view thereof.

FIG. 10 is a top plan view thereof.

FIG. 11 is a right side elevation view thereof. The left side elevation view is the mirror image of the right side elevation view.

FIG. 12 is a bottom plan view thereof.

FIG. 13 is a front elevation view thereof; and,

FIG. 14 is a rear elevation view thereof.

The broken lines in the drawings depict features that form no part of the claimed design.

1 Claim, 10 Drawing Sheets
